UNITED STATES PATENT OFFICE

124,153

DESIGN FOR AN ADVERTISING DISPLAY STAND

Joseph S. Harrison, Atlanta, Ga.

Application March 6, 1940, Serial No. 90,728

Term of patent 3½ years

To all whom it may concern:

Be it known that I, Joseph S. Harrison, a citizen of the United States, residing at Atlanta, in the county of Fulton and State of Georgia, have invented a new, original, and ornamental Design for an Advertising Display Stand, of which the following is a specification, reference being had to the accompanying drawing, forming part thereof.

In the drawing:

Fig. 1 is a front elevational view of an advertising display stand, showing my new design; and

Fig. 2 is a top plan view thereof.

The rear of the article is substantially the same as the front illustrated in Fig. 1.

I claim:

The ornamental design for an advertising display stand, as shown and described.

JOSEPH S. HARRISON.
